UNITED STATES PATENT OFFICE.

PAUL GAGNEAU, OF PARIS, FRANCE.

MAGAZINE FOR TICKETS.

Application filed March 18, 1926, Serial No. 95,689, and in France April 3, 1925.

This invention relates to magazines for tickets to be used in following the movements of railway cars.

- In prior devices of this kind, railway cars 5 have been equipped with a pair of ticket boxes placed at each end of the car, each box containing a certain number of tickets bearing the number of the car, its special characteristics and whatever other information desired. 10 A ticket taken from one of these boxes and sent to the central control office immediately gives the information necessary to trace the various movements of the car. This system, however has one very serious disadvantage. 15 When all the tickets have been removed from the boxes—and this frequently happens when the car is at some distance from its base—there is no convenient means for resupplying the boxes or for otherwise continuing the 20 ticket system of control.

- The present invention aims to remedy the above mentioned disadvantage by means of a specially contrived ticket-box having both a replaceable and a reserve magazine therein. 25 The invention aims further to so arrange the replaceable and reserve magazines that neither of these can be easily removed, tampered with or destroyed by malicious persons.

- The invention will now be described with 30 reference to the accompanying drawings in which:—

Fig. 1 shows an elevation of the device.

Fig. 2 is a perspective view of the replaceable ticket magazine.

- Fig. 3 is a section through line 3—3, Fig. 1, showing the box containing a supply of tickets.

Fig. 4 is a section of the replaceable magazine taken on line 4—4, Fig. 1.

- Fig. 5 is another section of the replaceable magazine taken on line 5—5.

Fig. 6 is a section through the magazine lock taken through line 6—6, Fig. 4.

- Fig. 7 shows a control ticket to be used with 15 the box.

Turning to the drawings *a* represents a rectangular box having a removable front closure *b*. Closure *b* is hinged to the top of the box and has lateral extensions or aprons 50 for protecting the box against rain and snow. The box is attached to the railway car by means of screws *c*. The box is arranged to receive a replaceable magazine *d* consisting of a U-shaped steel band which fits against surfaces *a*¹ at the back of the box so as to cover screws *c* and prevent the latter being tam-

pered with. The lateral branches of member *d* are bent at *d*¹ so as to fit into recesses *a*² formed in the walls of box *a*. The magazine is held firmly in place by its own elasticity and by the interengagement of the bulged portions *d*¹ in recesses *a*². Tickets are attached to magazine *d* by means of the longitudinal bar *e* and the bolts *f* passing through the ticket perforations. Bolts *f* are 60 preferably arranged so that the nuts which hold them in place face the back of box *a*. This arrangement prevents bar *e* and bolts *f* being removed from the front of the box. Magazine *d* is locked in position preferably 65 by screw clamps *h* mounted on the lateral walls of box *a* in housings *i*, the clamps being so located that they clear band *d* when they are loosened by key *i*¹. The magazine is 70 in this manner, locked in the box and can be 75 removed only by the person properly authorized to remove it.

To permit reprints to be made of the tickets at any place, a die *j* (Fig. 3) is mounted with 80 one of the ticket piles on one of the bolts *f*. The die thus mounted cannot be removed without taking magazine *d* out of the ticket box.

In the event that the supply of tickets attached to bolts *f* becomes exhausted and it is 85 desired to renew the supply immediately, a supplementary ticket magazine *k*, fixed to the back of box *a* by bolt *l*, is provided. This reserve magazine *k*, it will be noted, cannot be 90 reached without removing magazine *d*. It 95 serves to supply control tickets during the intervals in which a new supply of tickets is being printed from die *j* for the main magazine *d*. Preferably, for reasons to be explained later the tickets in magazine *k* are 100 made up in a different color from those in magazine *d*.

From the foregoing description, it will be 105 clear that the ticket box here provided can carry a supply of control tickets under all ordinary conditions. Whenever the main magazine is exhausted, it is removed and a new supply of tickets is struck off from die *j* at the station where the car happens to be, reserve magazine *k* supplying tickets until 110 main magazine *d* is refilled and replaced.

If the magazine *d* is not replaced before the car leaves a given station or if, for any reason, a new supply of tickets is not printed, the movements of the car can be recorded on 110 tickets taken from reserve magazine *k*. Tickets from the latter magazine, on reaching

the central office,—since they are of a special color—give notice of the condition of main magazine *d*. A fresh magazine may therefore be immediately despatched from the central office to replace the one which is deficient.

What I claim is:—

1. In a ticket control device, the combination of a box, a reserve ticket magazine connected to the rear wall of said box, a detachable main ticket magazine located in the front of the box and having detachable means for holding tickets, said detachable means being connected to the rear of said main magazine by fastening means non-accessible at the front 10 of said main magazine, and at the rear of the rear wall of said box, and locking means adapted to hold said main magazine in position.
2. A ticket control device comprising a box, 20 a reserve ticket magazine connected to the rear wall of said box by fastening means detachable only at the front of said rear wall, a removable front main ticket magazine having a rear wall fitting over said reserve ticket 25 magazine and having ticket holding means connected thereto, by fastening means detachable only behind the said rear wall of said main magazine, and locking means for holding said main magazine in position.
3. In a ticket control device, the combination of a box, a U-shaped member fitting within the said box, a ticket clamping bar associated with said U-shaped member, bolts

adapted to hold tickets between the rear wall 35 of the said U-shaped member and the said ticket clamping bar, nuts associated with said bolts behind the rear wall of the said U-shaped member, and locking means adapted to engage the said U-shaped member and to lock it in position in the box.

4. In a ticket control device, a box, a ticket magazine fitting into said box, said magazine comprising a ticket supporting frame and means for clamping tickets onto said frame, and clamping means engaging with said 45 ticket supporting frame and operable to clamp the magazine in the box.

5. In a ticket control device, the combination of a box, a reserve ticket magazine, a U-shaped member fitting over said reserve 50 magazine, a ticket clamping bar, means for clamping tickets between said clamping bar and said U-shaped member and means for locking said U-shaped member in the box.

6. In a ticket control device, the combination of a box, a reserve ticket magazine, a U-shaped member fitting over said ticket magazine, a ticket clamping bar, a bolt for clamping tickets between said clamping bar and U-shaped member and a screw clamp attached to 60 the box and operable to clamp the U-shaped member over the reserve ticket magazine.

In testimony whereof I have hereunto set my hand.

PAUL GAGNEAU
